ATTORNEY.

UNITED STATES PATENT OFFICE.

WALTER C. PITTS, OF PHILADELPHIA, PENNSYLVANIA, ASSIGNOR TO
VICTOR TALKING MACHINE COMPANY, A CORPORATION OF NEW
JERSEY.

DESIGN FOR A CABINET FOR TALKING-MACHINES.

No. 38,113.

Specification for Design.

Patented July 3, 1906.

Application filed May 12, 1906. Serial No. 316,555. Term of patent 14 years.

To all whom it may concern:

Be it known that I, WALTER C. PITTS, a citizen of the United States, and a resident of Philadelphia, in the county of Philadelphia, State of Pennsylvania, have invented a new, original, and ornamental Design for Cabinets for Talking-Machines, of which the following is a specification, reference being had to the accompanying drawing, forming a part thereof.

The drawing shows a perspective view of the cabinet embodying my design.

What I claim is—

The ornamental design for cabinet for talking-machines as shown.

WALTER C. PITTS.
